Patented Dec. 9, 1919.

UNITED STATES PATENT OFFICE.

AUGUST J. GRENZIG, OF BROOKLYN, NEW YORK.

ADJUSTABLE HAMMER-STAND.

1,324,394.

Specification of Letters Patent.

Patented Dec. 9, 1919.

Application filed April 19, 1917. Serial No. 163,217.

To all whom it may concern:

Be it known that I, AUGUST J. GRENZIG, a citizen of the United States, and a resident of New York, borough of Brooklyn, county of Kings, and State of New York, have invented a certain new and useful Improvement in Adjustable Hammer-Stands, of which the following is a full, clear, and exact specification.

10 This invention relates more particularly to an apparatus for use in conjunction with a class of hammer and drilling tools. My invention has for its object primarily to provide a stand adapted to be employed 15 for permitting a hammer especially of electrically operative, or pneumatic type to be supported in a manner whereby holes may be readily drilled, or bolts driven in parts of structures, such as the ceilings of a building, 20 when made particularly of concrete and like hard material, and which is of a form whereby the hammer may be raised and lowered to different heights, in order to allow the work to be accomplished on ceilings of various 25 elevations. The invention consists essentially of a base with a tubular standard projecting upwardly therefrom, and movable inwardly and outwardly of the upper end of the standard is a tubular member. Adapted 30 to be extensibly adjusted inwardly and outwardly of the upper end of the standard is an upright member, and on this upright member is a bracket for removably carrying a hammer so as to be guided in the radius 35 of a circle.

Other objects of the invention are to provide a manually operative lifting device for elevating the tubular member and the upright to various heights; to provide a retainer for releasably locking the upright when adjusted in the tubular member; and to provide a stand of a simple, efficient and durable construction which may be made in various sizes.

45 A practical embodiment of the invention is represented in the accompanying drawing forming a part of this specification in which similar characters of reference indicate corresponding parts in all the views, and will 50 then be pointed out in the claims at the end of the description.

In the drawing, Figure 1 is an elevation of one form of adjustable hammer stand embodying my invention showing the manner of its use for supporting a hammer.

Fig. 2 is an enlarged fragmentary sec-

tional view, partly in detail and partly broken away, taken on the line II—II of Fig. 1 with the hammer removed therefrom.

Fig. 3 is an enlarged fragmentary sectional view, partly in detail, taken through the lower part of the stand.

Fig. 4 is an enlarged top plan of the bracket used in the stand for carrying the hammer.

Fig. 5 is a pronged cap employed in the stand.

Fig. 6 is an inverted plan of the pronged cap, and

Fig. 7 is an elevation of the tubular stand used in the stand.

The apparatus, or stand has a base 10 which may be of any suitable shape and size, and this base may be mounted on rollers, as 11, if desired. On the central part of the top of the base 10 is provided an interiorly threaded boss, as 12, in which is screwed the lower exteriorly threaded end of a tubular standard, or pipe 13 of a length 75 to extend a suitable distance above the base, and lengthwise of the central part of this standard is a slot 14. On the upper end of the tubular standard 13 is a cap 15 having an opening 16 in register with the passage 80 of the tubular standard, and movable inwardly and outwardly of the upper end of the standard through the opening of its cap is a tubular member 17.

The tubular member 17 is in the form of 90 a pipe of a length for being raised and lowered to various heights relative to the top of the standard 13, and on the lower end of this tubular member interiorly of the standard is a cap 18 with depending prongs, as 95 19. Transversely through the prongs 19 are registered orifices 20 and 20^a, and the end wall of the groove between these prongs may be beveled on an upward incline, as at 21. On the upper end of the tubular member 17 is provided a cap 22 having an opening 23 leading into the passage of the tubular member, and extensibly adjustable inwardly and outwardly of the tubular member 17 through its cap 22 is an upright member 24.

The upright member 24 is preferably in the form of a rod of a length whereby its upper end may be elevated a desired height above the tubular member, and at spaced intervals in this upright, or rod 24 may be a 110 number of orifices 25 each adapted to be registered with apertures 26 and 26^a provided

in opposite parts of the cap 22 of the tubular member 17.

The upper end of the upright may be threaded, and on this threaded end is rigidly held between two nuts 27 and 28 the apertured central part of the transverse arm 29 of a bracket 30 which is of a substantially U-shape to provide two spaced arms 31 and 32 projecting upwardly from the ends of the transverse arm 29. Between the arms 31 and 32 is a clamping element 33 preferably in the form of a ring or band 34 of spring metal, and protruding laterally from opposite parts of this ring are short studs 35 and 36 which are journaled in the upper ends of the vertical arms of the bracket 30 so that the clamping ring 33 may be swung in upwardly and downwardly directions in the bracket. Part of the ring 34 of the clamping element is split, and these ends of the ring are bent outwardly therefrom to provide two parallel arranged lugs, as 37 and 38, adapted to be normally sprung from each other by the tension of the ring, and these lugs may be releasably locked to each other by means of a screw bolt, as 39, being screwed through registered threaded holes in these lugs. This clamping element serves to permit an electrically-operative, or pneumatic hammer of any well known, or preferred type, as 40, to be removably carried in the bracket for driving bolts, or drilling holes in places at high elevations, such as the cement ceiling of a building or other structure, and to mount the hammer in the clamping element the bolt 39 is loosened in the lugs of the spring ring 33, and this ring is then guided over the nozzle portion of the hammer, after which the bolt is tightened in the lugs of the ring 40 for removably holding the hammer in the clamping element for being swung in the bracket 30 in desired directions.

In order to allow the upright member 24, bracket 30 and hammer 40 to be releasably held when adjustably raised or lowered in the tubular member 19, a retainer 41 is provided. The retainer 41 is preferably made with a sleeve, or ring 42 which is slidably arranged on the upright member, and fastened to opposite parts of the sleeve are one of the ends of two chains 43 and 44 having on their other ends pins 45 and 46, respectively. The sleeve 42 of the retainer 41 is smaller in diameter than the cap 22 of the tubular member 17 so as to rest upon this cap when the upright member is adjusted in the tubular member, and by inserting the pins 45 and 46 through the apertures 26 and 26^a of the cap 22 and into one of the orifices 25 of the upright member this member with the bracket 30 and the hammer 40 will be releasably locked against movement when raised or lowered relative to the tubular member 17 and to the standard 13.

During the drilling of a hole, or driving

a bolt into a place at a high elevation it is necessary to gradually raise the hammer as the work progresses, and in order to move the hammer as may be required the bracket 30 with the upright member 24 and the tubular member 17 are manually forced upward by means of a lifting device, as 47. This lifting device has a lever 48 in the form of a bar with one of its ends being movably disposed through the slot 14 of the standard 13, and the end of this lever within the standard is pivoted between the prongs 19 of the cap 18 of the tubular member 17 by a bolt 49 being passed through the orifices 20 and 20^a of these prongs as well as through an opening in the lever. On the second end of the lever 48 may be a handle 50, and the central part of the lever is pivoted, at 51, to the upper end of a curved bar 52 having its lower end pivoted, at 53, to a bracket 54 secured to the standard 13 at the lower end of its slot 14. When the lever 48 with its handle 50 is swung downwardly the second end of the lever will contact with the beveled part 21 of the cap 22 of the tubular member 17, and this tubular member with the upright member 24, bracket 30 and hammer 40 will then be forced upwardly as well as being held at the desired height by the operator of the lifting device continuing to force the handle 50 in a downward direction. In this manner a simple, efficient and durable stand is provided whereby an electrically-operative, or pneumatic hammer may be conveniently used at high elevations.

In the foregoing description I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:

1. The combination with a base, a tool supporting member having means to removably secure a tool thereto, and means to vertically adjust said tool supporting member relative to said base to initially set the tool engaged with its work, of means to subsequently gradually vertically move said tool supporting member relative to the base to feed the tool upwardly to its work as the latter progresses.

2. The combination with a base, a tool supporting member operatively disposed directly above said base and having means revoluble about a horizontal axis to removably secure a tool thereto, and means to vertically adjust said tool supporting member relative to said base to initially set the tool

engaged with its work, of means to subsequently gradually vertically move said tool supporting member relative to the base to feed the tool upwardly to its work as the latter progresses.

3. In a tool stand, a base, a tubular upright standard mounted on the base, a tubular member movable inwardly and outwardly of the upper end of the standard, an upright member supporting a tool retaining means on the upper end thereof and adjustable inwardly and outwardly of the upper ends of the tubular member to initially engage the tool with its work, a retaining means for releasably holding the upright member adjusted in the tubular member, and a manually operable lifting means for gradually simultaneously elevating the tubular member and the upright member relative to the tubular standard to feed the tool to its work as the latter progresses.
4. In a tool stand, a base, a tubular upright standard mounted on the base, a tubular member movable inwardly and outwardly of the upper end of the standard, an upright member adjustable inwardly and outwardly of the upper end of the tubular member to initially engage the tool with its work, a tool retaining means, a bracket on the upper end of the upright member supporting the tool retaining means, a retaining means for releasably holding the upright member adjusted in the tubular member and a manually operable lever on the standard pivotally connected directly to the tubular member for gradually simultaneously elevating the tubular member and the upright member relative to the standard to feed the tool to its work as the latter progresses.

5. The combination with a base having an upright standard rigidly mounted centrally thereon, a member freely vertically slidable relative to said standard, means to gradually vertically slide said member, a second member vertically slidable relative to said first named slidable member and the standard, and means to retain said slidable members in relative adjusted positions, of a tool supporting member upon the upper end of said second slidable member and provided with means to removably secure a tool thereto directly above said standard and both slidable members.

6. A tool stand including a base, an upright tubular standard rigidly mounted on said base and provided with a longitudinal elongated slot, a tubular member slidably disposed within and projecting beyond the upper end of said standard, a curved link having one end pivoted to said standard adjacent the bottom of said slot, a hand lever having the other end of said link pivoted thereto between the ends thereof, said hand lever extending through said slot into the standard and directly pivotally connected to the lower end of said tubular member, a rod slidably disposed within and projecting beyond the upper end of said tubular member, means to retain said rod in slidably adjusted positions relative to the tubular member, and means carried by the upper end of said rod for removably retaining a tool.

This specification signed and witnessed this 18th day of April A. D. 1917.

AUGUST J. GRENZIG.
